TION OF NEW YORK

ROLLING EYES FOR DOLLS

Application filed November 1, 1927. Serial No. 230,230.

This invention relates to an improvement in rolling eyes for dolls.

An object of the invention is to provide an eye set in which the eyes are capable of a generous degree of pivotal movement in all directions about their spherical centres and in which provision is made for easy and convenient universal adjustment of the eyes with respect to each other about their spherical centres.

A further object is to provide an eye set as above indicated and in which the eyes are readily adjustable toward and away from each other.

15 A further object is to provide an eye set in which there is employed a horizontal carrier designed to be permanently connected in position within the doll head and upon which the eyes are mounted for universal rotary movement and manual adjustment.

A more specific object is to provide an eye set comprising a horizontal carrier designed to be permanently connected in position within the doll head and having a pair of 25 bracket members longitudinally slidably adjustable thereon each serving to support one of the eyes, and to provide means connecting the eyes for simultaneous oscillatory movement.

30 A further object is to provide an eye set comprising two independently mounted eyes, a connection between said eyes by which the eyes are caused to oscillate in unison, and said connection including a part serving as a bumper for limiting movement of the eyes.

Other objects and aims of the invention, more or less specific than those referred to above, will be in part obvious and in part 40 pointed out in the course of the following description of the elements, combinations, arrangements of parts and applications of principles constituting the invention; and the scope of protection contemplated will be indicated in the appended claims.

In the accompanying drawings which are to be taken as a part of this specification, and in which I have shown merely a preferred form of embodiment of the invention:—

Fig. 1 is a rear elevational view of an eye set constructed in accordance with this invention, a part of the set being broken away and shown in section for better disclosing the details of construction, and the whole being illustrated in position within a doll head appearing in vertical section.

55 Fig. 2 is a horizontal sectional view taken upon the plane of line II—II of Fig. 1.

Fig. 3 is a vertical sectional view taken 60 upon the plane of line III—III of Fig. 1.

Fig. 4 is a vertical sectional view taken 65 upon the plane of line IV—IV of Fig. 1.

Fig. 5 is an enlarged fragmentary perspective view of parts of the eye set appearing in the above figures.

Fig. 6 is a view similar to that shown in Fig. 1 but illustrating a modified form of the eye set.

Fig. 7 is a horizontal sectional view taken 70 upon the plane of line VII—VII of Fig. 6.

Fig. 8 is a vertical sectional view taken 75 upon the plane of line VIII—VIII of Fig. 7, and

Fig. 9 is a horizontal sectional view taken 80 upon the plane of line IX—IX of Fig. 6.

Referring to the drawings for describing in detail the invention as shown therein, and referring first to the structure appearing in Figs. 1 to 5, the reference character L indicates a doll head having the usual eye openings as 1 and 2 therein at opposite sides of the central or nose portion 3.

The eye set consists of a horizontal supporting carrier as G of the general type as shown in the pending application of Alexander Konoff, Serial No. 141,943, Patent No. 1,726,184, dated August 27, 1929 in that it comprises a main body member 4 upon which is slidably mounted a pair of attaching members as 5—5 adapted to be thrust from opposite ends of the body into firm attachment with the side walls of the doll head to thereby rigidly connect the carrier in position spanning the interior of the head. Slidably mounted also upon the body of the carrier G is a pair of bracket members as 6—6. These project forwardly from the carrier toward the eye openings 1 and 2 and each is 95 100

adapted to support one of the eye members or shells H.

The bracket members 6 may be connected with the carrier in any appropriate manner but as illustrated each consists of a piece of sheet metal folded over upon itself to provide opposite legs one of which as indicated by the reference character 7 being shaped to fit about the upper longitudinal margin of the carrier and the other as 8 being shaped to fit about the lower margin of the carrier, the two legs thus so engaging the carrier as to permit the brackets to be moved longitudinally along the carrier. It is intended that the fit of the legs upon the carrier shall be sufficiently loose so that the brackets may move longitudinally of the carrier with great ease, whereby to facilitate the automatic centering of the eye shells within the eye openings 1 and 2 of the head.

The portion of each bracket which extends forwardly of the carrier is provided with pivot extensions as 9 and 10 thereon. These extensions define a horizontal pivot upon which is mounted a cage 11.

The cage 11 as illustrated is formed from a single piece of sheet metal having a main part 12 and a pair of side arms as 13 and 14 extending therefrom. The arm 13 has a pivot opening as 15 for receiving the pivot 9 and the arm 14 has a similar pivot opening for receiving the pivot 10. The main part 12 has also an upwardly positioned arm 17 and a downwardly positioned arm 18 and these have pivot openings as 19 and 20 therethrough respectively within which is rotatably mounted the upper end portion as 21 of a weight arm 22, said weight arm continuing downwardly and being connected at its lower end as at 23 with one side of a weight as 24, the other side of the weight being connected at the lower end of the second weight arm as at 25 so that the weight is supported in common by the two weight arms and imposes its force of gravity equally upon said weight arms, it being here noted that the connection at the point indicated by the reference characters 23 and 25 is in the form of a universal joint permitting the weight arms to move in all directions with respect to the weight.

The bracket members 6 are cut away at their forward ends as at 26 to accommodate the weight arms without interference to the free pivotal movement of the cages upon the brackets.

The eyes H may be formed in any appropriate manner and may be connected with the weight arms by any suitable means. According to the structure illustrated in Figs. 1 to 5 however each eye is made up of inner and outer semispherical shell members as 27 and 28 respectively. These may be of any appropriate material but usually sheet metal is employed for the inner shell and celluloid

for the outer shell, the two shells being fitted snugly one within the other but there being sufficient freedom of movement between the shells so that the outer shell may be rotatably adjusted about its spherical centre when found necessary. The inner shell is provided with a suitable number of radial slits as 29 therein rendering it of a springy character so that it will serve to apply a spring friction resistance to movement of the outer shell sufficient to retain the outer shell in any position to which it is rotatably adjusted, after the manner as more fully shown and described in the pending application of Samuel Marcus and Alexander Konoff, Serial No. 216,530, Patent No. 1,727,477, dated September 10, 1929.

As a means of attaching the eyes on to the weight arms, each of the inner eye shells 27 is shown to be provided with upper and lower sections bent inwardly from the normal spherical contours of the eye shells arranged to provide upper and lower connecting arms as 30 and 31 projecting rearwardly from an inner point of the eye shells and each having an opening as 32 therein arranged to snugly and tightly engage upon the weight arm.

Although the connecting arms 30 and 31 are intended to engage the weight arms with sufficient rigidity to cause the eyes to at all times move with the weight arms during the normal functioning of the eyes in use, it is desirable nevertheless that the joint between the connecting arms and the weight arms shall be such as to permit of a ready manual adjustment of the eye shells about their respective weight arms whenever found necessary. To this end it is suggested that the connecting arms 30 and 31 be so formed as to provide small sleeve extensions as 33 about the openings 32 for thereby elongating the walls of the opening for engaging the weight arm, thus to increase the frictional grip of said walls upon the weight arm. In conjunction with this each of the connecting arms is provided with a slit as 34 outwardly from the openings 32 so that the walls of the openings 32 are rendered suitably resilient to thereby provide a strong spring friction engagement of said walls against the surface of the weight arm. By making the openings 32 slightly smaller than the diameter of the weight arm ample frictional grip is provided when the parts are forced together during assembly of the set.

The connecting arms 30 and 31 are spaced apart a distance slightly greater than the distance between the arms 17 and 18 of the cage 11 so as to provide for a limited vertical movement of the eyes, with their connected weight arms, with respect to the bracket members 6, this being a further provision for enabling the eyes to automatically find their proper centres of rotation within the eye openings 1 and 2 of the head.

The side arm 14 of each cage member is provided with a lateral extension as 35, said extensions from the two eyes being directed toward each other and being slideable through rectangular openings as 36 provided to receive them in a central member 37 which also constitutes a bumper to limit pivotal movement of the eyes. This central member as shown is formed from a single piece of sheet metal having a main part 38 at opposite sides of which are flanges 39 and 40 formed with the rectangular openings 36 respectively. From the main part there also extends a downward projection 41 which constitutes a bumper proper, the lower end being intended to engage against the inner surface portion of the head for limiting pivotal movement of the eyes about the pivots 9 and 10, as clearly illustrated in Fig. 4. The extension 41 is sufficiently long so that it is of considerable resilience thus constituting a resilient bumper for arresting pivotal movement of the eyes without noise.

If desired a similar extension as 42 may be provided at the upper edge of the main part 38 adapted to engage the doll head for limiting pivotal movement in the opposite direction.

At their adjacent ends each of the extensions 35 are provided with a stop lug as 43 adapted to engage the inner surfaces of the flanges 39 and 40 to prevent disconnection of the extensions from the bumper member.

It is particularly pointed out that owing to the rectangular cross sectional contour of the extensions 35, and the fact that they engage within correspondingly shaped rectangular openings 36 of the bumper member it follows that the sliding movement of the extensions through the rectangular openings will permit easy movement of the eyes toward and away from each other along the supporting carrier, but will cause the rotary movements of the eyes during normal operation to be in unison.

It is here to be noted however that the extensions 35 are readily bendable under force of manual pressure whenever it is desired to adjust the eyes with respect to each other about their horizontal pivots. A slight rotary movement of one eye, by manual pressure, with respect to the other eye may cause a slight twisting of one or both of the extensions, but this will to no appreciable extent interfere with the normal function of the bumper member.

In attaching this eye set within a doll head the set is placed upon a suitable tool. The doll head is introduced over the set in position so that the eye openings of the head properly receive the eye shells. The shells will move toward or away from each other to a suitable degree to permit them to readily enter the eye openings. If the appearance of the eyes as viewed exteriorly of the head in-

dicates a necessity for adjusting one eye relatively with respect to the other about the horizontal pivots 9—10, or about its horizontal pivot around the inner shell member, or about its vertical pivot connection with the weight arm, the eyes may be relatively removed from the head, the adjustment made and the eyes again returned. When the adjustments have been completed and the eyes are seen to occupy their proper positions within the eye openings of the head the attaching members of the supporting carrier are then thrust outwardly to fasten the whole within the doll head. The slight looseness provided in the pivot connection of the eyes with the cages 11 will permit of a smooth oscillatory movement of the eyes by gravity within the eye openings of the head at all times even if the final positioning of the supporting carrier is not precisely accurate, that is to say that any slight deviation of the pivots 9 and 10 from the exact spherical centre of the circle defined by the eye openings of the head will be compensated for by the looseness of connection between the eyes and the bracket members. And it is here pointed out that the pivot extensions 9 and 10 are preferably sufficiently smaller than the pivots 15 and 16 so that an appreciable amount of looseness is present.

In the structure illustrated in Figs. 6 to 9 the horizontal supporting carrier G is utilized. The slidably mounted bracket members 43—43, corresponding with the bracket members 6—6 of the previous figures are used for the same purpose as before. In this instance however they each consist of a single piece of sheet metal having upper and lower marginal parts as 44 and 45 bent to engage about the supporting carrier, and having other parts struck out and bent to constitute a pair of forwardly extending arms as 46 and 47, said arms having aligned bearing openings as 48 and 49 within which engage a pair of pivot extensions as 50 and 51 projecting from opposite sides of a small collar 52 which is loosely mounted upon the upper end portion 21 of the weight arm, the pivotal connection thus provided between the weight arm and the bracket members being on a horizontal plane and said bearings of the two eyes being in alignment and substantially intersecting the spherical centres of the eye shells as is the case with the pivotal connection provided between the cages 11 and the bracket members 6—6 of the previous figures.

The pivotal connection of the arms with the collar 52 on a horizontal axis, and of the collar with the weight arm on a vertical axis, constitutes a universal pivot for the eyes upon the bracket members.

To retain the collar 52 against moving longitudinally of the weight arm, and also to thereby retain the horizontal axis of rotation at a point intersecting the spherical centre

of the eye shell, a back plate as 53 is provided at the rear of the eye shell serving to connect said shell with the weight arm and providing upper and lower shoulders as 54 and 55 spaced 5 apart and receiving the collar 52 between them.

This back plate 53 is connected with the weight arm in a manner providing a friction grip upon said weight arm for at once permitting manual adjustment of the eye shell 10 rotatably of the weight arm and holding the eye shell in any position to which it is adjusted rotatably upon the weight arm. The means employed for providing friction grip 15 of the back plate upon the weight arm may take any desired form, but in the instance illustrated in these figures it consists in reversely bending adjacent portions as 56 and 57 of the plate above and below the collar 52 20 so that a passage-way is provided between them to receive the weight arm, the natural tendency of the reversely bent portions to return toward their original position serving to tightly grip against the weight arm, as will 25 be readily understood upon inspection of the drawings.

The back plate 53 may be connected with the eye shells in any approved manner but preferably is provided with a suitable number 30 of extending parts as 58 and 59 resting against the rear annular edge surface of the eye shell, and held there by turned-over tangs as 60 provided upon the shell and engaging about the annular edge part of the back plate.

35 This manner of connecting the back plate with the eye shell provides for convenient adjustment of the eye shell rotatably about a horizontal axis transverse to a line extending between the two eyes, it being here noted that the extensions 58 and 59 are 40 suitably spaced from the tangs 60, and that the tangs engage edge parts of the back plate which are concentric with the spherical centre of the shell so that the shells may be 45 moved rotatably about the mentioned axis within sufficiently generous limits to provide all necessary adjustment.

In this instance the representation of an iris may be carried directly upon the eye shell which is here shown as being a single shell, indicated by the reference character 61, 50 corresponding with the inner shell 27 of the previous figures. The outer shell as 28 shown in the previous figures may be used if desired, but is not required here in-so-far as 55 the matter of providing for adjustment about the mentioned horizontal axis is concerned.

As a means for insuring simultaneous oscillatory movement of the eyes about their aligned horizontal pivots during normal operation, the drawings Figs. 6 to 9 suggest the use of a connecting member as 62 which extends between and engages about the two 65 weight arms. This connecting member is

preferably made from a strip of sheet metal bent at its opposite ends so as to provide loops as at 63 and 64 within which the weight arms loosely engage, said loops being elongated in the direction of the length of said member, as most clearly seen in Fig. 9, so that the weight arms, with their respective eyes and bracket members, may be free to move longitudinally of the supporting carrier G. The strip of material from which the connecting member is made is of sufficient width, and the parts comprising the loops 70 75 80 85 90 95 100 105 110 115 120 125 130 135 140 145 150 155 160 165 170 by which the eyes and weight arms are pivotally connected with the carrier.

2. In combination, an eye set comprising a pair of eyes spaced apart, a supporting carrier for the eyes extending longitudinally substantially parallel with a line between the eyes, a pair of separately formed brackets one arranged adjacent each end of the supporting carrier and slidably mounted thereon to move toward and away from each other, said bracket and said eyes having co-operative pivot parts by which the eyes are universally pivotally connected with the brackets respectively, weight arms depending from the eyes, a weight connected with said arms whereby to move the eyes by gravity upon their universal pivotal supports, each eye having an arm projecting laterally therefrom toward the other eye and independent of the weight arms, and a member engaged by said laterally projecting arms to be moved thereby when the eyes are swung by the weight in one direction, said member constituting a bumper to limit the swinging movement of the eyes.

3. In combination, an eye set comprising a pair of eyes spaced apart, a supporting carrier for the eyes extending longitudinally substantially parallel with a line between the eyes, a pair of separately formed brackets one arranged adjacent each end of the supporting carrier and slidably mounted thereon to move toward and away from each other, a pair of weight arms one for each eye, connections including parts of the weight arms by which the eyes are pivotally connected with the brackets respectively, a weight connected with said arms whereby to move the eyes by gravity upon their pivotal connection with the brackets, each eye having an arm projecting laterally therefrom toward the other eye, and a member engaged by said laterally projecting arms to be moved thereby when the eyes are swung by the weight in one direction, said member constituting a bumper to limit the swinging movement of the eyes.

4. In combination, an eye set comprising a pair of eyes spaced apart, a supporting carrier for the eyes extending longitudinally substantially parallel with a line between the eyes, a pair of separately formed brackets one arranged adjacent each end of the supporting carrier and slidably mounted thereon to move toward and away from each other, a pair of members pivotally connected one with each of said brackets to swing upon a common horizontal axis, connecting means for said members having parts co-operative with said members to insure their pivotal movement in unison while permitting movement of said members toward and away from each other, a pair of weight arms one pivotally connected with each of said members to swing upon vertical axes, said weight arms being off-set and weighted at their lower ends, and parts

carried by the eyes respectively engaging said weight arms to connect the eyes to swing with the weight arms, said parts being constructed to provide spring frictional grip upon the weight arms for thereby affording adjustment of the eyes with respect to the weight arms.

5. In an eye set, an eye, a supporting carrier, a weight, a weight arm having a cylindrical portion, the eye having a back plate formed with reversely bent parts providing a spring socket within which the cylindrical portion of the weight arm engages to frictionally retain the eye rotatably and slidably adjustably connected with the weight arm, the back plate having portions constituting a pair of shoulders spaced apart in the direction of length of the mentioned portion of the weight arm, a collar loosely rotatable upon said mentioned portion of the weight arm having a part projecting between said shoulders to provide pivotal connection between the eye and the collar about a relatively vertical axis, and means providing pivotal connection between the collar and said supporting carrier upon a relatively horizontal axis.

In testimony whereof we affix our signatures.

SAMUEL MARCUS.
ALEXANDER KONOFF.
